DARK CLOSURE

Frank W. Swormstedt, Fort Thomas, Ky., assignor to Higgin Products, Inc., Newport, Ky., a corporation of Delaware

Application March 15, 1940, Serial No. 324,222

2 Claims. (Cl. 160—21)

My invention is addressed to the problem of producing shades which will effectively darken a room, not in the sense of such light-tight closures as would have to be employed over the windows of a photographic dark room, but in the sense of a shade of opaque character to be drawn over the window opening after the manner of an ordinary window shade, and equipped with means for excluding light around the edges of the closures.

Such closures are of utility in school rooms, lecture halls and the like, where substantial darkening is desired without absolute light-tightness, and at low cost.

The problem is one of providing a structure to be used with a shade of ordinary construction and employing the ordinary spring roller. An aspect of the problem is the provision of a structure capable of quantity production in standardized form, but which is adjustable to fit window openings of a very wide variety of sizes. The exigencies of the problem include the provision of a housing for the roller sufficient to cut off light passing between the window opening and the roller, which housing must be adjustable, the provision of side guides to enclose the edges of the closure and prevent substantial light leakage there, which guides must likewise be adjustable, and the provision of a reinforcement intermediate the length of the closure when drawn, which reinforcement must likewise be adjustable, all at the minimum of expense.

The primary object of my invention is the solution of these problems. Other objects will be set forth hereinafter or will be apparent to one skilled in the art upon reading these specifications. Reference is made to the drawing wherein:

Figure 1 is an elevational view of a window opening equipped with my closure.

Fig. 2 is a sectional view through the roller and housing taken along the lines 2—2 of Fig. 1.

Fig. 3 is a sectional view through a guide and a portion of the closure taken along the lines 3—3 of Fig. 1.

Fig. 4 is a somewhat similar sectional view taken along the lines 4—4 of Fig. 1 and showing the coaction of the reinforcement with the guides.

Figs. 5 and 6 are perspective views of the end members on the housing.

Figs. 7 and 8 are respectively perspective views of the end portions of the lateral walls of the roller housing.

Fig. 9 is a perspective view of an end of the reinforcement.

Fig. 10 is a sectional view through the reinforcement taken along the lines 10—10 of Fig. 1.

5 In the practice of my invention, in its general aspect, I provide end members for a roller housing, which members incorporate the usual supports for a spring roller of the ordinary type. To form the lateral walls of the roller housing, 10 I provide telescoping members having engagement with the said end pieces. I provide side guides of telescopic formation adapted to be adjusted to the height of the window opening, and I provide a reinforcement also of telescopic construction, having engagement with the side guides and adapted to rest upon an upper portion of the lower telescopic section of the side guides. The closure itself is preferably of the ordinary window shade construction, the spring roller being that in current use, and the material of the shade being opaque. The usual draw bar is employed and need not be modified except for the attachment of small and simple means for raising the reinforcement. Thus, I 15 provide a series of parts which may be used with shades and rollers of current manufacture where dark closures are desired, and may even be separately sold and applied to shades already installed.

20 30 In Figure 1, I have shown a window opening generally at 1 provided with a shade 5 on a roller 6. As shown in Fig. 2 the roller is of the usual hollow wooden construction 7 with the interior spring 8. It is provided with the usual end pieces 9.

35 40 Instead of employing the usual shade roller brackets, I incorporate the holding portions of the bracket structures in end wall pieces for a roller housing. These end pieces are illustrated, 45 in one form, in Figs. 5 and 6. Each comprises a body 11 having an angularly related attachment portion 12. The body 11 is shaped to form an end of a housing enclosing the roller. To the bodies 11 I attach respectively the holder 13 for the circular projection on one of the end pieces 9 and the holder 14 for the flattened projection at the other end piece of the spring roller. While I have shown these holders separately formed and attached as by spot welding to the bodies 11, it will be within the skill of the worker in the art to form the housing end pieces by extending so as to include configurations acting as the holders, if this be desired.

50 55 For the lateral walls of the roller housing, I employ the telescopic members 15 and 16

shown in Figs. 7 and 8. The member 16 is a sheet metal member bent in simple U shape. The member 15 is a similarly shaped sheet metal member adapted to fit on the outside of the member 16 and having turned-over portions 17 and 18 at its respective edges. It will be understood from the several figures how the member 16 (with its edges engaged by the turned-over portions 17 and 18) will fit in the member 15 slidably. The members 15 and 16 have portions 19 and 20 respectively struck inwardly to form sockets for engagement of prongs or arms on the housing end pieces. These prongs or arms are shown at 21 in Figs. 5 and 6.

The side guides are sheet metal members of generally U shaped cross section and of telescopic form. An upper section 22 is made to slide over the body of a lower section 23 of each guide; but the side edges of the lower guide part are turned back over the edges of the upper guide part as shown at 24 in Fig. 3. The back leg of the U shape of each section is usually made the longer, and is perforated at intervals for the reception of attachment screws 25. The front leg has matching perforations 26, but of a diameter large enough to permit the passage of the heads of the screws. Both edges of each guide part may be rolled or beaded if desired, and still the interfitting relation essentially illustrated in Figs. 3 and 4 obtained. The guide sections are of such character that they can be cut to desired lengths during installation, so that the upper end of the lower guide section will come approximately midway of the window opening for a purpose hereinafter to be described.

In installations of the type to which this invention is addressed, it is not ordinarily necessary to provide a guide or closure means at the bottom of the window opening for light-tight interengagement with the draw bar of the shade.

It is, however, usually requisite to provide reinforcement for the shade cloth midway of the window opening to prevent the closure from being blown inwardly and out of the guides if the window is open. I provide such a reinforcement in the form of a telescopic, hollow bar formed of bent or rolled sheet metal parts of a cross section such as that shown in Figure 10. The outer part 27 slidably embraces the inner part 28, so that the bar is adjustable as to length. The bar is intended to ride up and down with the closure along the outer leg of the upper side guide part 22. Each section has welded to it near its outer end an angularly bent piece of sheet metal 29, an end of which presents a tongue 30 adapted to ride inside the outer leg of the upper guide section. The reinforcement bar is thus guided upon the upper side guide section.

The relationship of the bar and tongue 30 is such, however, that the bar will not pass the upper end of the lower side guide section. Thus, when the shade is drawn, the bar occupies the position shown in Fig. 1. Small, angularly

shaped feet 31 are attached to the draw bar 32 of the shade closure, as may be done by riveting or bolting. When the shade is raised, these feet contact the reinforcing bar and carry it upwardly with the draw bar so as to leave the window opening unobstructed. In some installations I may desire to provide latches 33 on the sill for engagement with the feet. By the means heretofore described, and equivalents of them I have achieved an inexpensive structure which nevertheless is effective for the purpose set forth. It can be made in a single size, and adapted to the specific size of all window openings of ordinary dimensions. It comprises few parts; and these are simple. It employs ordinary closures and spring rollers. Modifications, especially as to the shape of the elements involved, may of course be made in my invention without departing from the spirit of it.

Having thus described my invention, what I claim as new and desire to secure by Letters Patent, is:

1. In a housing for a spring roller, substantially semi-circular end wall members each having an attachment foot, said end wall members shaped to provide respectively pivotal and non-pivotal support for a spring roller, and a pair of telescopic sections forming lateral wall portions of said housing, said sections having sockets on their ends, and said end wall members having pins to enter said sockets whereby the said lateral wall portions of said housing may be removed without disturbing the said end wall members.
2. In a dark closure, in combination with a spring roller, shade cloth and draw bar, a roller housing having lateral walls formed as interfitting, telescopic parts substantially U-shaped in cross-section and end-wall members having peripheral shape coinciding with the cross-sectional shape of said parts and being attachable to a window frame member, said end-wall members having means for attachment to the ends of said parts and shaped to provide respectively a pivotal and a non-pivotal support for said spring roller, telescopic side guides for engaging the edges of said shade cloth as it is withdrawn from said roller housing, said side guides each comprising a pair of interfitting, telescopic parts substantially U-shaped in cross-section, the lower one of said parts of each pair having an edge portion reversely bent about the edge portion of the upper one of said parts, and a reinforcing bar for the shade cloth slidable on the upper part of each of said side guides and adapted to rest upon the upper end of the lower part of each of said side guides, said reinforcing bar comprising two interfitting, telescopic parts, each of said parts having at one end means adapted to engage within the upper side guide part, said draw bar having feet thereon adapted to engage and raise said reinforcing bar.

FRANK W. SWORMSTEDT.
